US00D824708S

(12) **United States Design Patent** (10) Patent No.: **US D824,708 S**
(45) Date of Patent: ** Aug. 7, 2018

(54) **PARTITION PANEL FOR DESK**

(71) Applicant: **Okamura Corporation**, Yokohama-shi, Kanagawa (JP)

(72) Inventor: **Takayuki Yamamoto**, Yokohama (JP)

(73) Assignee: **Okamura Corporation**, Yokohama-shi, Kanagawa (JP)

(**) Term: **15 Years**

(21) Appl. No.: **29/602,612**

(22) Filed: **May 2, 2017**

(30) **Foreign Application Priority Data**

Nov. 4, 2016 (JP) 2016-024031

(51) LOC (11) Cl. **06-03**

(52) U.S. Cl.

USPC **D6/714**; D6/332; D6/643.1

(57) **CLAIM**

The ornamental design for a partition panel for desk, as shown and described.

DESCRIPTION

FIG. 1 is a front perspective view of a partition panel for desk showing my new design;

FIG. 2 is a front view thereof, the rear view thereof being a mirror image;

FIG. 3 is a right side view thereof, the left side view thereof being a mirror image;

FIG. 4 is a top view thereof;

FIG. 5 is a bottom view thereof; and,

FIG. 6 is a perspective view of usage.

The broken lines in FIGS. 1-3 and 5 are for the purpose of illustrating portions of the partition panel for desk and form no part of the claimed design. The broken lines in FIG. 6 are for the purpose of illustrating the environmental structure and form no part of the claimed design.

1 Claim, 4 Drawing Sheets
